W. KELLY,
WELL POINT,
APPLICATION FILED APR. 25, 1917.

1,256,906.

Patented Feb. 19, 1918.

William Kelly, ^{Inventor},
By Frank A. Aulmann, ^{Attorney}

UNITED STATES PATENT OFFICE.

WILLIAM KELLY, OF GRAND ISLAND, NEBRASKA.

WELL-POINT.

1,256,906.

Specification of Letters Patent. Patented Feb. 19, 1918.

Application filed April 25, 1917. Serial No. 164,437.

To all whom it may concern:

Be it known that I, WILLIAM KELLY, a citizen of the United States of America, and resident of Grand Island, in the county of Hall and State of Nebraska, have invented 5 certain new and useful Improvements in Well-Points, of which the following is a specification.

This invention relates to well points and 10 particularly to casings adapted for use in wells, the same being of a sectional type and provided with means whereby they are bound together in a manner to afford means of communication between the external and 15 internal surfaces of the said casings at the joints, means being provided for permitting liquid to find its way to the passages of the joints while at the same time preventing the accumulation of foreign substances such as 20 gravel, dirt, and the like into the ducts or passages or in the interior of the casing.

A further object of this invention is to 25 provide means for holding the sections of the casing in spaced relation to each other and provide a bearing whereby one may be supported on the other while they are, at the same time, bound together, as stated.

With the foregoing and other objects in 30 view, the invention consists in the details of construction, and in the arrangement and combination of parts to be hereinafter more fully set forth and claimed.

In describing the invention in detail, 35 reference will be had to the accompanying drawings forming part of this specification, wherein like characters denote corresponding parts in the several views, and in which—

Figure 1 illustrates a vertical sectional 40 view of a portion of a well point embodying the invention;

Fig. 2 illustrates a plan view of one of the sections of the casing on an enlarged scale; and

Fig. 3 illustrates an enlarged detail vertical sectional view through a fragment of two of the sections on a line corresponding with the line 3—3 of Fig. 2.

In these drawings 4 denotes a series of 50 sections which are of uniform construction and each of said sections has a series of slots 5 in its outer wall, the said slots being flared inwardly from the surface so that the size of each opening increases from the said sur-

face inwardly. The function or purpose of 55 these slots is to permit water or fluid to run or percolate through the restricted openings while at the same time precluding the entrance of gravel, dirt or the like, the said fluid then gravitating to the lower end of 60 the section where it will be permitted to reach the interior of the casing, as will presently appear.

The ends of the sections are beveled inwardly as at 6 so that when the sections are 65 superimposed, one upon the other, the space between them increases from the edges to the inner surfaces so that fluid may more readily find its way to the interior of the casing. When fluid passes down the slots 70 into the space 6, it may flow to the interior of the casing comparatively free of impurities such as gravel, dirt or the like. The ends of the sections have corresponding lugs 7 which are adapted to abut when one section 75 is placed on the other and these lugs form bearings so that when the sections are bound together, as will presently appear, one is firmly seated on the other.

In order to provide means for building up 80 the sections while at the same time binding them together, each section has a plurality of longitudinally disposed apertures 8 which are adapted to align when the sections are 85 assembled with relation to one another and I preferably employ four of said apertures in each section. Binding rods 9 extend through the apertures of the sections and I prefer that two of the rods shall extend through two sections and that another pair 90 of binding rods extend through two sections whereas they are stepped with relation to the other two rods. By this arrangement, two rods will always extend above one of the sections, thus facilitating the placing of the 95 sections since the projecting rods will facilitate the application of the sections to those previously placed and they can be bound together by nuts 10 threaded on the bolts.

I claim—

1. A well point comprising sectional casings, each having slots in its outer surface, the said slots being flared inwardly from the said outer surface, the ends of said sections being beveled inwardly, lugs at the ends of 105 said sections adapted to abut lugs of the contiguous sections, said sections having longitudinally disposed apertures, and sets

of bolts extending through said sections, one set of bolts being in stepped relation to the other set of bolts.

2. In a well point, sectional casings, each having slots extending longitudinally thereof from end to end, the ends of the said sections being beveled, lugs on the said ends adapted to engage lugs of the contiguous

sections, said sections having apertures therethrough, bolts projecting through apertures of two contiguous sections, and bolts extending through other apertures of each of said sections and through apertures of other contiguous sections. **10**

WILLIAM KELLY.
